UNITED STATES PATENT OFFICE.

EDWIN A. WEBSTER, OF HAVERHILL, MASSACHUSETTS, ASSIGNOR, BY MESNE ASSIGNMENTS, TO HAMEL SHOE MACHINERY COMPANY, OF LYNN, MASSACHUSETTS, A CORPORATION OF MASSACHUSETTS.

HEEL-BREASTING MACHINE.

1,170,374.

Specification of Letters Patent.

Patented Feb. 1, 1916.

Application filed May 16, 1914. Serial No. 839,147.

To all whom it may concern:

Be it known that I, EDWIN A. WEBSTER, a citizen of the United States, residing at Haverhill, in the county of Essex and State 5 of Massachusetts, have invented an Improvement in Heel-Breasting Machines, of which the following is a specification.

This invention relates to that class of heel-breasting machines which are primarily designed for use in breasting leather "Louis" heels, and, more particularly, to that type of machine employing a reciprocating knife which is adapted to cut from side to side, or transversely of the heel in breasting the 15 same.

The object of my invention is to provide a machine of this type with means whereby the shoe may be quickly placed and securely held in the desired position for breasting, so 20 that the breasting operation may be quickly performed, without injury to the shoe, and further to provide means whereby the machine may be readily adapted for different styles and sizes of heels.

I accomplish these objects by the means shown in the accompanying drawing in which:—

Figure 1 is a front elevation of a heel-breasting machine embodying my invention. 30 Figs. 2 and 3 are side elevations of the head portion of the machine viewed from the left and from the right respectively. Fig. 4 is a sectional view of the knife clamp, taken on line 4—4 of Fig. 2. Fig. 5 is a horizontal sectional view on line 5—5 of Fig. 2. Fig. 6 is a detail view of the top-lift engaging plate. Fig. 7 is a detail sectional view of the heel-support.

The machine illustrated is of the well known foot-power type, comprising a frame 40 having a knife-carrier 11, mounted to reciprocate vertically therein, said carrier being connected to a treadle 12 by an intermediate link 13 and being provided with a 45 returning spring 14, as shown.

The breasting-knife 15 is arranged to depend vertically from the carrier 11 and is secured thereto by means of a knife-clamp, shown in detail in Fig. 4, comprising two 50 members 16 and 17, which are secured to the carrier by bolts 18, said knife being curved transversely to correspond to the particular shape, or curvature of the particular shape of heel-breast which is to be formed. A ver-

tically disposed post 19 is mounted in 55 brackets 20 and 21, secured to the front side of the machine, directly beneath the knife 15 and a heel-support is mounted on the upper end thereof, said support comprising a base 22 having an upwardly projecting heel-support 60 22' thereon. The upper surface of said support is inclined down from its side-face 22'', which face is perpendicular and is curved to correspond to the shape of the back of the breasting-knife and arranged 65 closely adjacent the path thereof, so that the cutting edge of the blade passes in close proximity to the raised edge of the support, whereby said edges may coöperate to act as a shear. The shearing edge of the support is 70 inclined upwardly from the outer end thereof to correspond with the ordinary taper of the heel, so that, when the side of the heel is laid thereon the top lift will be supported perpendicularly. As I prefer to perform the 75 heel-breasting operation before the heel is shaved, it is not necessary to have this edge fit against the side of the heel exactly.

The inclination of the top surface of the support 22' is such that the side of the heel, 80 when resting thereon, is only engaged by the shearing edge of said support, so that the heel may be tilted thereon to any angle at which it may be necessary to hold the heel to breast it at the desired angle, as indicated in 85 Fig. 7.

A shank rest 24, consisting of a vertically extending post, having a rounded surface, is secured at its lower end, to an angular shaped bracket 25, by a bolt 27, and said bracket is, in turn, secured to the post 19 by a bolt 26. Said shank rest is arranged adjacent the front end of the heel-support and extends adjacent and parallel to the side edge of the breasting-knife, which, when in 95 use, passes in close proximity to the shank of the shoe, and to permit said rest to be adjusted in the desired relation to said knife the openings through which said bolts 26 and 27 pass are elongated, so that it may be 100 moved from right to left and from front to rear.

A top-lift rest 30 is provided adjacent the inner end of the heel-rest 22', said top-lift rest being supported so that it may be 105 adjusted to varying conditions. The particular means which I employ for providing these adjustments may be described as fol-

lows:—A bracket 31 is clamped on the frame by means of a bolt passing through a vertical slot 32 in said bracket, to permit the same to be moved vertically and clamped in different positions of vertical adjustment. Said bracket 31 is further provided with horizontally disposed guideways, in which an angular shaped bracket 33 is mounted to slide and a bolt 34 passes through an elongated slot 33' therein, so that it may be moved forwardly and rearwardly and clamped in the different positions desired. The bracket 33 is also provided with guideways which extend at right angles to the guideways in the bracket 31, and a clip 35 is, in like manner, connected to the bracket 33 by a bolt 36 which passes through a longitudinal slot in said clip. The heel rest plate 30 is pivotally mounted on said clip 35, so that it may be tilted either to the right or the left, and a pair of stop-screws 37 are mounted therein at opposite sides of said pivot, so that, by loosening one of said screws and tightening up on the other, the plate may be held in different angular positions.

With the above described adjusting means, the plate 30 may be moved horizontally in the plane of its heel-engaging face according to variations in the pitch of the heels, or it may be moved horizontally from front to rear, at right angles to said face, according to variations in the height of the heels, and it may also be tilted to vary the angle at which the top-lift of the heel is held, that is, according to the tread of the heel.

In breasting a heel, the shoe is so placed in the machine, that the edge-portion of the heel rests on the shearing edge of the support, its top-lift rests flat against the plate 30 and its shank bears against the rest 24, the heel being tilted to the desired inclination on the heel-support. The treadle is then depressed and the knife forced downwardly, removing a chip from the breast of the heel and forming a breast face of the de-

sired shape. With the above described arrangement the shoe may be quickly placed in position and removed therefrom, and, as the breasting-operation may be done rapidly, the whole operation may be quickly and accurately performed. The machine may also be readily adjusted to varying conditions of pitch, height and tread, and, if the heel of a left shoe is to be breasted at a different angle than that of a right shoe, it is merely necessary to tilt the heel to the correct position.

I claim:—

1. A heel-breasting machine having a vertically reciprocating knife-holder, a breasting-knife depending therefrom and a heel-support having a vertical side face conforming to the back of said knife and disposed in close proximity to the path thereof to form a shearing edge, the top surface of said support being inclined downwardly from said edge to permit the heel to be tilted into different positions thereon, and a top-lift rest vertically disposed at the top-lift engaging end of said edge, substantially as described. 60

2. A heel-breasting machine having a vertically reciprocating knife-holder, a breasting-knife depending therefrom and a heel-support having a vertical side face conforming to the back of said knife and disposed in close proximity to the path thereof to form a shearing edge, the top surface of said support being inclined downwardly from said edge to permit the heel to be tilted into 75 different positions thereon, and a vertically extending shank-rest arranged adjacent the heel-base-engaging end of said edge, substantially as described. 80

In testimony whereof, I have signed my name to this specification, in the presence of two subscribing witnesses.

EDWIN A. WEBSTER.
